PAGE 2

FIG. 1 is a perspective view of a rotary wing aircraft or the like showing my new design;

FIG. 2 is a top plan view thereof;

FIG. 3 is an elevation view as seen from the right side thereof; the left side, not shown, is a mirror image of the right side;

FIG. 4 is a front elevation view thereof; and

FIG. 5 is a rear elevation view thereof.

The fragmentary showing of the rotor blades is for ease of illustration only.

This application is a continuation-in-part of my co-pending application Ser. No. D-8,165 filed Aug. 8, 1967.

I claim:

The ornamental design for a rotary wing aircraft or the like, substantially as shown and described.
